UNITED STATES PATENT OFFICE

2,603,908

DRAWING BOARD ATTACHMENT

Jacques Schwefel, Los Angeles, Calif.

Application May 11, 1950, Serial No. 161,338

2 Claims. (Cl. 45—131)

This invention relates to drawing boards and has special reference to an attachment for boards of this class, the device being preferably termed a drawing board apron.

In the use of drawing boards in which the distance from the edge at which the draftsman stands or sits to the opposite edge is inconveniently distant, difficulty is experienced in drawing on paper of corresponding distance between its top and bottom edges when fully exposed on the board. In the wider sheets of paper it is often necessary for the draftsman, in order to reach the upper part of the sheet, to stand on a stool or the like and assume a half reclining position.

One important object of this invention is to provide a novel attachment for drawing boards permitting the use of a sheet as wide or even wider than the board on which it is fastened while that part of the sheet on which the draftsman is working is at all times conveniently within his ordinary reach.

Draftsmen sometimes attempt to keep the upper part of a sheet pinned on a board conveniently in reach by allowing the lower part of the sheet to hang down over the front edge of the board. This not only tends to crease the sheet at the board edge but also exposes the part hanging down to contact with the draftsman's clothing and possibly becoming soiled.

Another object of the invention is to provide a drawing board attachment whereby the lower part of a sheet may hang over the front edge of a drawing board without creasing.

A further object of the invention is to provide a novel attachment for drawing boards so arranged as to guard a depending portion of a drafting sheet having its upper part pinned on the board from pressure by the draftsman's clothing.

With the above and other objects in view, as will be presently apparent, the invention consists in general of certain combinations of parts and arrangements of details hereinafter fully described, illustrated in the accompanying drawings and particularly claimed.

In the drawings, like characters of reference indicate like parts in the several views, and

Figure 1 is a perspective view of a drafting board with this attachment secured thereto.

Figure 2 is an enlarged detail section on line 2—2 of Figure 1.

Figure 3 is an enlarged detail section on line 3—3 of Figure 2, and

Figure 4 is a transverse section through a certain apron forming part of this invention.

In the embodiment of the invention disclosed in the drawings there is shown a drawing board 10 of the usual rectangular shape and having a forward edge 11 at which the draftsman stands or sits to work. With the distance from the edge 10 to the opposite edge 12 being too great for the draftsman to reach conveniently while drawing lines on paper pinned to the board, it becomes necessary for the draftsman to assume an awkward and uncomfortable position while drawing. As here shown, a sheet of drafting paper is illustrated on the board 10, the position of the sheet when entirely supported on the upper face of the board being shown in broken lines 13. This often brings the top edge of such a sheet too far from the draftsman who seeks to overcome this trouble by positioning the sheet as shown by the full lines 14 when working on the upper part of the sheet. In order to prevent the formation of a crease in the sheet by the upper angle of the edge 11 there is provided in the present invention a guard strip 15 one face 16 of which is flat. The other side of the strip 15 has a surface comprising a narrow arcuate portion 17 extending from the upper edge of the side 16 and, when the strip is secured to the board it is in such position that the upper surface of the board extends tangentially from the arcuate portion 17. This portion 17 merges smoothly into a wide arcuate surface 18 from which extends a flat tangential surface 19 leading to the lower edge of the face 16. The guard strip thus, as shown in Figure 2, prevents creasing of a sheet such as S when the lower part thereof depends from the front of the board 10. The use of the guard strip alone will not prevent rubbing of the draftsman's clothing against the sheet S at the front edge of the board. This guard strip is secured to the board by nails or screws as shown at 20.

In cooperation with the guard strip 15 there is provided an apron for preventing rubbing and soiling of the sheet S at the part depending over the guard strip. The apron is made of sheet metal, molded from plastic material or otherwise formed. The apron engages over the guard strip for its entire length and includes a longitudinally extending thin body portion having a narrow transversely arcuate portion 21 which merges into a wide transversely arcuate portion 22, the radii of these portions being longer than the respective radii of the strip 15 at 17 and 18. Extending tangentially from the portion 21 and, when mounted on the board 10, overlying the

front edge portion of said board is a cover strip 23. At each end of the cover strip 23 there is provided a downwardly directed integral spacer rib 24 for holding the cover strip in proper spaced relation above the board 10. Extending tangentially from the portion 22 at the lower edge thereof is a portion forming a sheet guide 25 which extends downwardly below and inwardly of the lower edge of the guard strip 15. At each end of the apron is a web 26 having a straight edge 27 in the plane of the face 16 to rest against the edge 11 of the board 10. This apron is attached to the board by nails or screws 28. As thus arranged, there is provided a continuous channel around the outer face of the guard strip with cover strips and guide strips extending from the upper and lower edges of this channel.

From the above detailed description of the invention, it is believed that the construction, use, and operation thereof will at once be apparent, and while there is herein shown and described the preferred embodiment of the invention, it is nevertheless to be understood that minor changes may be made therein without departing from the spirit and scope of the invention as claimed.

I claim:

1. A drawing board attachment including a guard strip having a flat surface to engage against one edge of a drawing board and having a curved surface over which drafting paper may travel, an apron having a curved portion extending around and spaced from said curved surface, said apron having a plane portion extending from said curved portion to overlie the board, means for securing said overlying portion to the top surface of the board, said apron having a plane paper guide portion extending downwardly from

the curved portion of the apron and across the plane of the flat side of the strip, and depending spacer ribs extending downwardly from the underside of the first mentioned plane portion of the apron to hold the same spaced from a board for the passage of paper beneath the apron.

2. A drawing board attachment including a guard strip having a flat surface to engage against one edge of a drawing board and having a curved surface over which drafting paper may travel, an apron having a curved portion extending around and spaced from said curved surface, said apron having a plane portion extending from said curved portion to overlie the board, means for securing said overlying portion to the top surface of the board, said apron having a plane paper guide portion extending downwardly from the curved portion of the apron and across the plane of the flat side of the strip, depending spacer ribs extending downwardly from the underside of the first-mentioned plane portion of the apron to hold the same spaced from a drawing board for the passage of paper beneath the apron and end webs on the apron overlying the ends of the guard strip.
